UNITED STATES PATENT OFFICE.

ANTHONY ZIMNIEWICZ, OF NEW YORK, N. Y., ASSIGNOR, BY MESNE ASSIGNMENTS, TO
MIEHLE PRINTING PRESS & MANUFACTURING COMPANY, OF CHICAGO, ILLINOIS, A
CORPORATION OF ILLINOIS.

ROTARY CUTTER.

Application filed December 15, 1924. Serial No. 756,110.

The present invention relates to improvements in rotary cutters especially adapted as an attachment for printing presses or folding machines, for cutting or slitting a 5 folded sheet or web of paper as it passes through the machine or press.

The primary object of the invention is the provision of a rotary cutter of this type for use in the manufacture of books, magazines and various other articles, which will insure a clean and uniform cut. To this end the invention consists in certain novel features of construction and combinations and arrangements of parts as will hereinafter 15 be more fully pointed out and claimed.

In the accompanying drawings I have illustrated one complete example of the physical embodiment of my invention wherein the parts are combined and arranged according to the best mode I have thus far devised for the practical application of the principles of my invention. While I shall refer to the machine of my invention as a 20 paper cutter, it will be understood that the invention is capable of use in various other ways, and therefore I do not limit myself to the physical embodiment of the invention as an attachment for folding or printing machines.

Figure 1 is a plan view showing so much of the machine as is necessary for an understanding of its construction and operation, the rotary cutter being illustrated in operative relation to the nipping or feed rolls for 35 the paper web or sheet.

Figure 2 is a view in elevation showing the parts of Figure 1, with the rotary cutter located below the longitudinal axis of the respective feed roll shafts.

Figure 3 is an end view of the parts shown in Figure 2, as seen from the left in the latter view, parts being shown in dotted lines for convenience of illustration.

Figure 4 is a detail sectional view at line 45 4-4 of Figure 2, showing the relation of the cutter and feed rolls to the leads of the paper web.

Figure 5 is an enlarged sectional detail view of the cutter and cutter-head and connections.

It will be understood that the device of the invention is designed to slit or cut the folded, or other edge, of a paper sheet or

web, and in the drawings the machine is adapted to cut the left edge of the paper in Figures 1 and 2, the leads of the paper being indicated in Figure 4 by the dotted lines with arrows.

In the drawings I have indicated as 1 a part of the frame of a printing or folding machine, together with a pair of roller shafts 2 and 3 having thereon the usual or standard form of nipping or feed rolls 4 and 5 arranged at suitable intervals and in the required number along the length of the shafts. The operating shaft 2 is shown as journaled in bearings in the frame 1, and this shaft may be driven from a suitable source of power for actuating both the feed rolls and the rotary cutter.

The short shaft 3 in the nature of a countershaft is disposed parallel with the operating shaft and in approximately the same horizontal plane, in order that the two sets of feed rolls 4 and 4' and 5 and 5' will register as complementary feed devices for the paper sheet or web. The feed shaft 3 is journaled in bearings 6 and 7, which as here shown form parts of supporting yokes 8 and 9. The shafts are shown as foreshortened for convenience of illustration and it will be understood that between these end yokes 8 and 9 other intermediate yokes are used if required. The yokes are fashioned with attaching hubs 10, 10 which are adjustable 85 both longitudinally and circumferentially on a supporting bar 11 which latter bar is located below the plane of the feed roll shafts.

By means of set bolts 12 carried by the hubs the yokes may be secured or fixed in adjusted position on the supporting bar 11.

The supporting bar or rod 11 is loosely supported in suitable bearings in the frame 1 as indicated by dotted lines in Figure 2, one end of the bar as shown projecting through the frame. This projecting end of the bar is provided with a lever 13 the hub 14 of which is fixed in adjusted position on the bar by means of a set bolt 15. The free end of the lever is equipped with a tension spring 16 which is anchored to a bracket 17 on the frame 1, and it will be apparent that the spring tends to rock the bar 11 in its bearings and swing the shaft 3 and its rolls 5 5' toward the shaft 2 and the com-

plementary feed rolls 4' to cause the rolls to nip or grip the paper sheet or web and feed the latter between the rolls.

The tension of the spring also maintains the rotary cutter in operative position and holds the cutter driving mechanism to its work, as will be described. The tension of the spring may be adjusted to vary the frictional contact between the feed rolls and to compensate for different adjusted positions of the rotary cutter, to suit different conditions.

The lead lines in Figure 4 and the arrows indicate the movement of the paper sheet or web as it is drawn through the two sets of feed or nipping rolls. The complementary rolls 4' and 5' as best seen in Figure 1 coact directly with the cutter blade 18 for slitting or cutting the edge of the paper sheet or web as it passes down between the two sets of feed rolls.

The rotary cutter-blade 18 is an open center, circular plate or disk, having a sharpened or beveled cutting edge, and the blade is attached by screws 19 (dotted lines Figure 5) to a cutter head 20. This circular cutter head 20 is fashioned with an integral or rigid, driven, gear wheel 21, and these members revolve upon a bearing bushing 22 which encases a spindle 23. The spindle or pin 23 is provided with a retaining head 24 which engages both the bushing 22 and the cutter head to hold these elements in operative position.

One end of the pin 23 is reduced as indicated at 25 and by means of this reduced portion the pin is supported in a boss 26 of a bracket 27, and securing or clamping nuts 28 on the threaded extremity of the reduced portion hold the cutter and cutter head in operative position and with stability. The bracket 27 is fashioned with a hub 28' which latter is secured in adjusted position on the bar 11 by means of a set bolt 29 carried by the hub 28' and designed to impinge against the surface of the bar 11. It will be apparent that the bracket carrying the cutter head and cutter may, through the hub 28' and set bolt 29, be adjusted both longitudinally and circumferentially of the bar 11 to accurately position the rotary cutter for the performance of its functions.

The rotary cutter is operated from the shaft 2 by means of a gear wheel 30 in engagement with the gear wheel 21 of the cutter head, and these gears are held in mesh by the tension of the spring 16 and lever 13, as will be readily understood.

Adjacent to the roller 4' of the shaft 2 a disk 31 is fixed to revolve with the shaft, and between this disk and the roller 4' an annular space 32 is formed into which the cutting edge of the rotary cutter projects, and by its co-action with the roll 4' the cutter severs or slits the edge of the paper sheet or

web as the latter moves between the feed rolls.

The rotary cutter in its relation to this cutting space or groove 32 may be adjusted to compensate for wear or to vary the penetration of the cutting edge of the blade across the edge of the paper sheet or web. This adjustment as before described may be accomplished through the hub 28' and set bolt 29, and wear may be taken up by adjusting the lever 13 through its hub 14 and bolt 15.

The axial center of the cutter it will be observed is located below the axial centers of the feed rolls and their shafts, and the cutting of the web takes place at approximately a point in alignment with the axial centers of the two sets of feed rollers or rolls.

The cutting edge of the cutter which engages the paper web or sheet at point 33 in Figure 4, thus co-acts with and severs or slits the web just at the point where the web is most rigidly gripped or held between the nipping or feed rolls, and at this point the greatest stability of the web is secured. Therefore the cutter is permitted to make a smooth and uniform cut of the web as it passes through the feed rolls.

Various changes may be made in the exemplification of my invention as illustrated in the drawings, within the scope of my appended claims, without departing from the spirit of my invention.

Having thus fully described my invention, what I claim as new and desire to secure by Letters Patent is:

1. The combination with an operating shaft and feed rolls thereon, of a support and adjustable yokes thereon, a shaft journaled in said yokes and complementary feed rolls on said shaft, a rotary cutter, a bracket for said cutter having an adjustable hub on said support, and resilient means connected to said support for maintaining said feed rolls and cutter in operative position.

2. The combination with a web feed mechanism of a supporting bar, a cutter bracket having a hub adjustable on said bar, a pin in said yoke, a rotary cutter head and cutter on said pin, means for operating said cutter head and cutter, and resilient means acting on said supporting bar for maintaining the rotary cutter in operative position.

3. The combination with a web feed mechanism of a supporting bar, a cutter bracket having a hub adjustable on said bar, a lever connected with said supporting bar and an anchored tension spring connected with said lever, a pin in said bracket, a rotary cutter head and cutter on said pin, and means for operating said cutter head.

In testimony whereof I have affixed my signature.

ANTHONY ZIMNIEWICZ.
